Primary Examiner — Sheryl Lane*Assistant Examiner* — Calvin E Vansant*(74) Attorney, Agent, or Firm* — David Guerra(57) **CLAIM**

The ornamental design for an ambidextrous locking instrument, as shown and described.

DESCRIPTION

FIG. 1 is a perspective view of an ambidextrous locking instrument showing our new design and in accordance with the new design;

FIG. 2 is a front elevational plane view thereof;

FIG. 3 is a rear elevational view thereof, with the front elevational view being a mirror image thereof;

FIG. 4 is a left side elevational view thereof;

FIG. 5 is a right side elevational view thereof, with the left side elevational view being a mirror image thereof;

FIG. 6 is a top plan view thereof; and,

FIG. 7 is a bottom plan view thereof.

The broken lines in FIGS. 1-7 illustrate portions of the ambidextrous locking instrument and form no part of the claimed design.

1 Claim, 5 Drawing Sheets(56)
